UNITED STATES PATENT OFFICE.

WILLIAM A. LORENZ, OF HARTFORD, CONNECTICUT.

HERMETIC CLOSURE FOR TUMBLERS.

No. 829,981.

Specification of Letters Patent.

Patented Sept. 4, 1906.

Application filed December 18, 1905. Serial No. 292,221.

To all whom it may concern:

Be it known that I, WILLIAM A. LORENZ, a citizen of the United States, and a resident of Hartford, in the county of Hartford and State of Connecticut, have invented certain new and useful Improvements in Hermetic Closures for Tumblers, of which the following is a full, clear, and exact specification.

This invention relates to improved means for hermetically sealing the tops of tumblers, mugs, and similar plain-rimmed receptacles, and is especially adapted for sealing by well-known vacuum processes.

Figure 1 of the drawings is a sectional view, in enlarged scale, of the left-hand upper side of a tumbler, showing my improved closure resting thereon in uncompressed or unsealed condition. Fig. 2 is a view similar to that of Fig. 1, but showing the closure in its compressed or sealed condition. Fig. 3 is a side view, in smaller scale, showing a sealed tumbler, the left-hand upper portion of which is broken away to show the closure-joint in section. Figs. 4, 5, and 6 are fragmentary views, in enlarged scale, illustrating the adaptability of this improved closure to the sealing of tumblers which are more or less irregular in the contour of their rims, these faults being liable to occur in the commercial manufacture of tumblers. Fig. 4 is a side view showing a depression in the upper surface of the tumbler-rim. Fig. 5 is a view in section taken on the line 5 5 of Fig. 4, showing the cross-sectional appearance of the depression of Fig. 4 and showing how my improved closure conforms to the depression during the sealing operation. Fig. 6 is a plan view showing a tumbler-rim which is unsymmetrical in its curvature. Fig. 7 is a fragmentary side view in section, taken on the line 7 7 of Fig. 6, showing how this improved closure compensates for the particular irregularity shown in Fig. 6.

In the hermetic sealing of tumblers and similar round-rimmed receptacles considerable difficulty has been experienced in providing a closure which will seat itself centrally and level upon the tumbler-rim and make an effective and permanent closure when sealed by known vacuum processes.

In tumblers, as in other receptacles for household use, particularly those intended for use at the table, it is desirable to avoid the use of sharp edges. Hence such utensils are made with a rim which is rounded in more or less approximation to a semicircle. In

the commercial manufacture of tumblers and similar articles of glass these rims are more or less liable to irregularities and other imperfections from wear or mismatching of the 60 mold and mold-rings by which these tumblers are formed. In order to minimize these imperfections and to produce the well-known bright glazed appearance, these tumblers are subsequently subjected to a fire-finishing operation in which they are subjected for a short time to a melting heat, usually from a gas-flame, which is directed so as to impinge upon the tumbler-rim, the tumblers being slowly turned with the object to bring all 70 portions of the rim uniformly under the action of the flame. This fire-finishing operation, however, frequently fails to remove the original imperfections and frequently adds other imperfections of its own, due to the unequal application of the heat to different portions of the rim, thereby melting down some portions more than others, as illustrated at 24 in Figs. 4 and 5, and also making the inner and outer contour of the same portion of the 80 rim unsymmetrical.

To provide compact self-contained and close-fitting closures for the tops of these commercial tumblers is the principal object of the present invention. This comprises a 85 closure consisting of a cap having a flexible flange of substantially cylindrical form which approximately fits the outer circumference of the tumbler-rim, combined with a flexible lining-gasket for the flange having an 90 acute-angled lower outer corner, which in the initial position of the closure and prior to the sealing operation projects downwardly into the small annular space lying outside of the rounded crown of the tumbler-rim and below 95 the level thereof, this downwardly-projecting portion being caught at the beginning of the downward sealing movement and receiving the entire sealing pressure is compressed and wedged into the said annular space during the whole of the downward sealing movement. This action greatly increases the chances of making a perfect seal as compared with those closures employing a gasket of round, square, or other compact cross-section in which the sealing movement itself is utilized to distort the original form of the gasket, and thereby produce a more or less blunt and irregular projecting fin, which toward the conclusion of the sealing operation 105 is more or less imperfectly projected across the sealing-joint too late in the sealing opera-

tion to insure uniform entry and distribution all around the joint.

The tumbler 10 is of the ordinary well-known form having a rounded rim. The cap 13 is made of sheet metal or other flexible material, and in its preferred simplest form shown herein it has a flat top 14 and cylindrical flange 15, which is made of a size to approximately fit the outer sides of the tumbler-rim 11. The flexibility of this rim enables it to conform to a considerable extent to moderate departures from a circular form of tumbler-rim.

The gasket 18 approximately fits the interior of the cap-flange 15 and is provided with a downwardly and outwardly inclined lower side, which may be either straight or curved and which in the initial or unsealed position of the closure rests upon the tumbler-rim 11 with its acute-angled outer annular corner projecting into the approximately triangular space lying at the outer side of the rounded crown 12 of the tumbler-rim. In order to enable the closures to be manufactured complete ready for use and handled separately from the tumbler, the gasket in its free condition is preferably made slightly larger than the cap and is slightly compressed therein. It may, however, if desired, be cemented in place, and in that case it is not necessary to make the gasket of a larger diameter.

The advantage of having the annular outer corner of the gasket lie closely against the interior of the cap-flange is that the corner is thereby disposed immediately above the joint between the cap-flange and the tumbler-rim, being thereby in a position to be drawn and wedged into that joint during the entire sealing operation, the acute angle of the corner enabling the sharp edge to project well into that joint at the very beginning of that operation. A further important advantage of this gasket having an acute-angled outer edge or corner is that the downwardly and outwardly inclined lower edge of the gasket is enabled to slide down toward the outer side of the rim, thus aiding in the general tendency to direct and compress the lower portion of the gasket into the aforesaid triangular space lying outside and below the level of the crown 12 of the tumbler-rim.

In the case of an imperfection like the depression 24 in the upper portion of the rim of the tumbler, as shown in Figs. 4 and 5, the vertical thickness or cushion of rubber lying immediately above and just outside of the rim is sufficient to compensate for a considerable depression. Moreover, such a depression does not materially affect the joint between the outer side of the rim and the cap-flange at this point; since the depression is in a direction parallel with the vertical flange 15 and has no more serious result than to depress the line of sealing-contact at that point.

In the class of imperfections shown in Figs.

6 and 8, which represent the rim as being flattened somewhat at 25 from its circular form the flattening opens a slight space between the rim and the cap-flange, as shown in section in Fig. 7, which space has no more serious result than to permit the edge of the gasket to be crowded down a little farther at this point.

During the sealing operation as the closure is moved downwardly from its initial position (shown in Fig. 1) toward its sealed position (shown in Fig. 2) the acute-angled annular corner 19 is at once pushed firmly downward into the joint between the inner side of the cap-flange 15 and the outer side of the tumbler-rim, thus pinching the corner of the gasket between those surfaces, and thereby tending to draw it by friction as well as to force it by pressure still farther into the joint as the downward movement continues. In this way the principal zone of seal is established approximately at the line 20. The continued compression of the gasket tends to carry the surplus upper and inner portion of the gasket inwardly over the tumbler-rim between the top of that rim and the under side of the cap, these surfaces serving also to compress the gasket between them and generally to force it outwardly toward the outer corner of the cap and into the joint. The cap is entirely free from the tumbler at all times, being supported wholly by the gasket. Therefore the cap remains at all times free to settle down under the pressure. The increased cushioning effect obtained by this closure does not necessarily involve the use of an increased amount of gasket material, but is mainly effected by the proper initial disposition and distribution of the gasket material in connection with the use of a flexible cap having a suitable contour for directing the flow of the gasket material during compression toward the desired sealing zone instead of allowing a considerable volume of it to protrude uselessly at one or both sides of the actual sealing zone. These improved closures are self-contained and may be manufactured and sold independently of the tumblers themselves. They may be sealed upon the tumblers in various well-known ways which are employed for effecting a vacuum-seal.

I prefer, however, to employ the process described and claimed in United States Patent No. 711,431, of October 14, 1902. It is obvious, however, that these closures could be sealed in any other well-known ways either by hot or cold processing.

I claim as my invention—

1. The combination with a receptacle having a rounded rim, of a hermetic closure therefore comprising a cap having a substantially cylindrical flexible flange approximately fitting the outer surface of the receptacle-rim, and a flexible gasket supporting the entire pressure of the cap, and having a cylindrical

- outer surface fitting the interior of the said flange and in its unsealed condition having a lower outer corner disposed at an acute angle lying close to the inner side of the cap-flange.
- 5 2. The combination with a tumbler or similar round-rimmed receptacle, of a hermetic closure comprising a cap having a flexible and substantially cylindrical flange approximately fitting the outer circumference 25 of the receptacle-rim, and a substantially cylindrical gasket the vertical height of which is greater than the thickness of its wall, the lower outer corner of the said wall being disposed at an acute angle lying close to the inner surface of the cap-flange.
- 10 3. The combination with a tumbler or similar receptacle having a rounded rim, of a hermetic closure therefor, comprising a cap having a flexible flange formed substantially 30 at right angles with the top of the cap and ap-
- proximately fitting the outer circumference of the receptacle-rim, and a substantially cylindrical gasket having a cross-section the vertical height of which is greater than its thickness, and the lower outer corner of 25 which is disposed at an acute angle lying close to the inner surface of the cap-flange, whereby the said acute-angled edge of the gasket in its unsealed condition projects into the annular space lying between the rounded 30 side of the receptacle-rim and the inner surface of the cap-flange.

In witness whereof I have signed my name to this specification in the presence of two subscribing witnesses.

WILLIAM A. LORENZ.
